Walter R. Kopp, New Haven, Conn., assignor to Olin Industries, Inc.

Application October 10, 1947, Serial No. 141,846

Term of patent 14 years

(Cl. D48—24)

To all whom it may concern:

Be it known, that I, Walter R. Kopp, a citizen of the United States, residing at New Haven, in the county of New Haven and State of Connecticut, have invented a new, original, and ornamental Design for Hand Lamp, of which the following is a specification, reference being had to the accompanying drawing, forming a part thereof.

In the drawing,

Fig. 1 is a top plan view of a hand lamp embodying my new design;

Fig. 2 is a side elevation;

Fig. 3 is a bottom plan view; and

Fig. 4 is an end elevation.

I claim:
The ornamental design for a hand lamp, as shown.

WALTER R. KOPP.
